UNITED STATES PATENT OFFICE.

WINFIELD H. YOST, OF MONTREAL, QUEBEC, CANADA, ASSIGNOR TO HARRY STILLSON
HART, OF CHICAGO, ILLINOIS.

DRAFT-RIGGING FOR RAILWAY-CARS.

1,195,943.

Specification of Letters Patent.

Patented Aug. 22, 1916.

Application filed January 7, 1911. Serial No. 601,429.

To all whom it may concern:

Be it known that I, WINFIELD H. YOST, a citizen of the United States, residing at Montreal, in the Province of Quebec and 5 Dominion of Canada, have invented certain new and useful Improvements in Draft-Rigging for Railway-Cars, of which the following is a description.

The object of my invention is to provide 10 a draft rigging for railway cars whereby the draw-bar will be yieldingly connected with the draft timbers of the car; the construction of the rigging being such that application of force on the draw-bar will meet 15 with a yielding resistance, and when the force is removed, the recoil will be reduced to a minimum.

The purpose of my invention is to provide 20 a lever mechanism so constructed as to prevent any displacement thereof during its movement; and one which will return to normal position as soon as force on the draw-bar is removed.

Another object of my invention is to provide 25 lever mechanism in which the levers, in addition to relieving the springs, perform the functions of followers and enable the latter to be dispensed with.

A further object of my invention is to 30 provide a lever mechanism which is so constructed and assembled, that the forces caused through the action of the draw-bar on the levers, and the levers on the intermediate springs, and the levers on their ful- 35 crum points on the draft timbers, will be in substantially parallel lines and also be parallel with the center line and sides of the car, thus preventing undue strains or any spreading tendency of the center sills 40 of the car; the mechanism being so constructed that movement of the levers in relation to each other will be made positive, as will more fully appear from the following detailed description.

45 In the drawing: Figure 1 is a horizontal central sectional view of my invention, looking downwardly. Fig. 2 is a transverse sectional view taken on the line *a—a* of Fig. 1, looking in the direction of the arrows. 50 Fig. 3 is a perspective view of two of the levers showing the same in position to be assembled, or placed one on top of the other.

55 1, 1 are cheek plates or members secured to the draft timbers or members 2. The

cheek plates or members are provided at opposite ends with draft-lugs 3, 3 and 4, 4; that is, a set of draft-lugs 3 and 4 is provided at each end of the cheek plates as clearly shown in Fig. 1.

5 is a draw-bar to which the coupler, not shown, is secured, the draw-bar being suitably mounted in the car frame and provided with a tail strap or yoke 5^a, which latter is secured to the draw-bar by rivets or in any other suitable manner. At each end of the cheek plates, as clearly illustrated in Fig. 1, I provide the superimposed levers 6 and 7. Plates 8 and 9 are inserted between the cheek plates with the concentric springs 10 and 11 inserted between the plates 8 and 9, and bearing against the same, thereby holding the plates 8 and 9 against the inner ends of the levers 6 and 7 of both sets at opposite ends of the cheek plates. Springs 10 and 11 hold the plates 8 and 9 in frictional engagement with the levers and form a yielding resistance to the movement of the levers and the draw-bar with relation to the draft-timbers. The lever mechanism consists of oppositely movable members, and I prefer to employ two sets or pairs of levers 6 and 7 at each end of the mechanism as clearly shown in Fig. 1. The inner ends 60 of levers 6 are provided with vertically extending lugs 12, while the levers 7 are provided at their inner ends with the vertically extending lugs 13. The levers 6 and 7 are also provided at a point intermediate of their ends and on the adjacent or contacting surfaces thereof with the ribs or flanges 14 and 15.

65 When the levers are assembled the lugs 12 and 13 will bear against the narrower sides of the correlated or adjacent levers, while 70 the ribs or flanges 14 and 15, which are formed in the arc of a circle, abut against each other and control the movement of the levers in both directions. The levers are 75 superimposed and arranged in pairs, by bringing the adjacent faces of the two levers, shown in Fig. 3, together, with the 80 ribs or flanges 14 and 15 abutting against each other. These flanges or ribs 14 and 15 will prevent any relative transverse movement of the levers, while the lugs 12 and 13 85 will cause the levers to interlock at the extreme point of their movement or travel in one direction, and while the levers are at 90 rest or in normal position, these lugs will 95 100 105 110

prevent further relative movement of the levers in the other direction. The outer ends of the levers which extend beyond the line of the draw-bar or yoke and in between the draft-lugs are so formed as to provide a square bearing on the draft-lugs, 3, 3 of the cheek plates, as clearly shown in Fig. 1, at 16. By forming the levers with the squared outer ends, the necessity for follower-plates intermediate of the levers and the yoke or draw-bar is obviated, because in operation the levers will bear flatly against the draft-lugs 3 and thus apply the force in a line substantially parallel with the sides 15 of the car; the levers 6 and 7 performing the same function as that performed by the follower-plates in constructions heretofore employed; that is, the levers will rotate when moved in one direction, using the yoke 20 or draw-bar as a bearing surface.

In the operation of the draft rigging, as shown in Fig. 1, when force is applied to move the car to the left the tail strap or yoke 5 will move the follower-levers 6 and 25 7 at the right of the figure bodily toward the left (compressing springs 10) until the outer, or fulcrum, ends of the follower-levers engage the draft lugs 4 at the right of the figure, the resistance to the movement of 30 the yoke up to this point being only that due to the direct expansive force of the springs. Further movement of the yoke to the left causes the follower-levers to rotate upon the draft lugs 4 as fulcrums, the yoke 35 bearing upon the sides of the levers and causing them to rotate and increase the resisting power of the springs by reason of the differential movement between the yoke and follower-levers. During the movement 40 of the follower-levers the correlated surfaces 14 and 15 of the respective levers bear against one another and prevent the levers sliding over one another and moving out of engagement with the draft lugs, these 45 surfaces also serving to insure uniform movement of both levers. In the event of the springs becoming broken, or of failure of some part, whereby the travel of the levers will be increased beyond the normal 50 limit, the lugs 12 and 13 will interlock and prevent the levers from rotating sufficiently to disengage from the draft lugs and so obviate total failure of the gear.

During the above described operation the 55 follower-levers at the other end of the gear remain immovable, the lugs 12 and 13 of the respective levers each bearing against the adjacent lever and causing the latter to interlock and form an abutment resisting the pressure of the springs, the ends of 60 the levers transmitting this pressure directly to the draft lugs 3.

As each end of the draft gear is exactly 65 similar in construction the operation of the gear when force is applied in the opposite

direction will be readily understood from the above description.

It will be noted that the levers 6 and 7, both while acting upon the springs to compress the latter when the force is in one 70 direction, and while transmitting the pressure of the springs to the draft lugs 3 when the force is in the opposite direction perform the functions of followers and so enable the latter to be dispensed with. 75

It is apparent from the construction shown and described, that at the extreme travel of the gear or draft rigging, the levers, which are provided with the squared outer ends, will have a full bearing on the 80 draft-lugs in such a manner as to cause all the forces to act in parallel lines, and by reason of the correlated or coacting ribs, prevent any spreading tendency of the 85 sills 2, 2. A suitable number of carriers 18 are employed, preferably two in number, made trough shaped and extending underneath the yoke and across from sill to sill; the carriers being fastened to the sills in any suitable manner. These carriers 18 90 not only form ties for holding the sills or cheek plates at a positive distance apart, but also carry the yoke 10 which in turn carries the entire draft gear.

The draft rigging is assembled in the 95 following manner:—Yoke 10, which may be formed as shown in the drawings, is connected to the coupler or draw-bar 5 in any suitable way and has fitted into it the two sets of superimposed levers 6 and 7, with 100 the springs 10 and 11 and plates 8 and 9 inserted between the two sets of the levers. The yoke with the levers and springs is then dropped in between the cheek plates 1, 1 in such a manner as to bring the outer ends 105 of the levers in proper place between the draft-lugs 3, 3 and 4, 4; it being understood that the cheek plates have previously been riveted or secured to the center sills 2, 2 of the car. After the mechanism has been 110 thus assembled and put into place, the carriers 18 are bolted to the sills as previously described, thereby completing the application of the gear or draft rigging to the car. In view of the frictional contact between 115 the outer ends of the levers and the draft-lugs 4, 4, I prefer to provide the cheek plates at the points 4, 4, which form the fulcrum points for the levers, with a hardened metal insert as shown at 19 in Fig. 1. By providing the fulcrum points 4, 4 of the cheek plates with the hardened metal 120 insert, the wear caused by the levers frictionally rocking about the points will be prevented. 125

The construction of draft rigging that I have described and illustrated in the drawing may be varied in certain minor details without departing from the spirit of my invention, as for example, the nature of the 130

coacting intermediate ribs or flanges on the adjacent faces of the levers may be modified, and I do not wish to be understood therefore as limiting myself to the exact construction illustrated, but

What I claim as my invention and wish to secure by Letters Patent is:—

1. A draft rigging for cars having levers whose outer ends project beyond the line of the draw-bar, and spring-mechanism interposed between oppositely arranged sets of said levers, said levers being provided at a point intermediate of their ends with abutting surfaces whereby relative transverse movement of the correlated levers is prevented, the outer ends of said levers being squared to form flat bearing surfaces against the draft-lugs.
2. A draft rigging for cars, comprising cheek plates provided with draft-lugs, means secured to the draft-lugs whereby wear thereon will be prevented, levers having rounded ends to permit of free movement and flat sides adapted to extend between the lugs to provide a flat bearing against one of the lugs, while the other side of the lever extends normally at an angle to the adjacent lug about which it is adapted to rotate, and spring mechanism arranged between the levers at opposite ends of the draft rigging.
3. A draft rigging for cars consisting of draft-lugs extending substantially at right angles to the draft timbers of the car, a yoke secured to the draw-bar, levers provided with correlated surfaces intermediate of their ends about which the adjacently placed levers rotate and movement lengthwise of each other is prevented, the inner ends of the levers being formed so as to prevent relative movement beyond predetermined points in a longitudinal direction, the sides of the levers being formed so as to provide substantially flat bearing surfaces for engagement with the draft-lugs and the ends of the

yoke whereby the lines of force are maintained parallel with the center line of the car, and spring mechanism interposed between said levers to provide a yielding resistance to the draw-bar.

50

4. A draft rigging for cars comprising draft-lugs, a draw-bar extension or yoke, levers provided with abutting surfaces to prevent relative movement in a direction lengthwise of the levers but permitting the same to rotate and having extensions arranged to engage the side of the adjacent lever, said levers being provided with flat surfaces arranged to bear against the lugs and the ends of the draw-bar extension whereby the lines of force are maintained parallel with the center line of the car.

55

5. In a draft rigging, spring mechanism, relief levers for the mechanism, said levers being at the end of the spring mechanism, draft lugs adapted to be engaged by the levers, such lugs being arranged on the opposite side of the levers to that upon which the spring mechanism is located, abutment surfaces adapted to be engaged by the levers, such abutment surfaces being arranged on the same side of the levers as is the spring mechanism, and a bearing member between the spring mechanism and levers, such bearing member being permanently out of contact with said abutment surfaces.

75

6. In a draft rigging, the combination with spring mechanism and draft lugs, of a lever adapted to act upon said mechanism, one end of the lever being located between the draft lugs and having one side formed to present a substantially flat bearing surface to one of the lugs, the opposite side normally extending at an angle to the surface of the other lug.
